United States Patent Office

Des. 188,885
Patented Sept. 20, 1960

188,885

GRILLE CLOTH

Sol A. Rosen, Highland Park, Ill., assignor to Solar Textile Co., Chicago, Ill., a corporation of Illinois

Filed Jan. 5, 1960, Ser. No. 58,931

Term of patent 3½ years

(Cl. D92—1)

I claim:

The ornamental design for a grille cloth, substantially as shown.
